UNITED STATES PATENT OFFICE

FREDERICK IRA BARKIS, OF LONG BEACH, CALIFORNIA

TONGS

Application filed March 29, 1930. Serial No. 439,975.

This invention relates to oil well apparatus, and particularly to an improved form of tongs.

The present invention presents many novel features over the conventional type of tongs.

The invention has for an object the provision of an improved form of tongs so constructed in such a manner that the gripping elements thereof more positively engage the work than is usually the case with the conventional type of tongs now in use.

Another object is the provision of a tongs wherein the work is readily gripped when the tongs is moved in one direction and the work released when the tongs is moved in a second direction.

Another object is to provide a tongs operating on a hydraulic principle.

Another object is the provision of a tongs which is simple of construction, positive in operation, and fool-proof.

In practicing the invention, I have provided a tongs including the usual head, an elongated handle associated therewith, which head carries one or more swing gates whereby work may be encompassed within the head, and jaws or grip members for engagement with the work. These jaws or grip members are urged into work engaging position through the medium of hydraulically operated pistons.

With the above named and other objects in view, the invention consists in the novel and useful provision, formation, construction, association, and relative arrangement of parts, members and features, all as shown in certain embodiments in the accompanying drawings, described generally, and more particularly pointed out in the claims.

In the drawings:

Figure 1 is a top plan view of the improved tongs.

Figure 2 is a cross sectional view on the line 2—2 of Figure 1 and on an enlarged scale,

Figure 3 is a sectional view on the line 3—3 of Figure 4,

Figure 4 is a sectional view on the line 4—4 of Figure 3, and

Figure 5 is a fragmentary sectional view on the line 5—5 of Figure 2.

Referring to the drawings, the tongs includes a handle *a* and a head *b*. The head includes a segmental part 1 and a pair of cooperating gates 2 and 3 hinged to said part 1. Any conventional form of latch 4 may be provided for locking the gates in work relation. These gates are provided with segmental work-receiving portions as is likewise the part 1. The part 1 of the head is provided with one or more spaced transverse bores 5.

Referring to Figure 2, a jaw arrangement is described, it being understood that the same arrangement could be followed out for any number of jaws. The part 1 is transversely bored as shown at 5, and a second transverse bore 6 communicates with the bore 5. A jaw is shown at 7 and this jaw is provided with a segmental part 8 provided with an arcuate face 9, and this jaw carries a slit 10. Connected with the jaw is a piston 11, this piston being received within the bore 5. The piston is provided at its working end with a cup rubber or gasket 12. The part 1 is recessed at 13 so as to accommodate the shank portion 14 of the jaw. This jaw is normally maintained within the recess 13 or the position shown in Figure 1, wherein it

will be noted that the jaw is out of work engagement, the work being indicated by dotted lines 15. This position is normally maintained by the means illustrated in Figure 2, constituting a pin 16 passed through bores 17 and 18 in the part 1 secured to the shank by screw-threads or otherwise, as indicated at 19. Within the bore 17 and surrounding the pin is a coil spring 20. In actual practice, I use upper and lower and oppositely arranged pins 16 in order to hold the jaw in what may be termed a neutral position. This construction is shown in Figure 5. As stated, I may provide any number of jaws, although in the present instance, I

have provided two and communication is afforded between both transverse bores 6 by means of piping 21. This piping may be held within the bores in any suitable manner,

such as by brazing or the like, as indicated in Figure 2, at 22.

In the present instance, the handle *a* is formed so as to hold a length of piping 23, 5 which is in communication with the piping 21. Any other construction would do, as long as communication was afforded with the piping 21. However, the present construction renders the piping 23 fool-proof. 10 For instance, the handle is provided with two side wall portions 24 and 25 joined to the head portion 1 and with an intermediate web 26 between said side walls, the web being provided with two upstanding flange members 27 and 28. Between these flange members 27 and 28 is placed the piping 23. The side walls 24 and 25 and the flanges 27 and 28 are merged together at 29. The part 29 is bored at 30 and the piping 23 communicates with said bore, as shown at 31. Within said bore is what may be termed a ram or piston 32, the construction of which is identical for the piston members for the jaws. The piston 32 is provided with a cup-shaped 25 rubber or gasket 33 and has connected therewith a push rod or stem 34 passed through stuffing or gland nuts 35, one of which nuts is screw-threaded to the end of the part 29, as shown at 36. The stem 34 is provided with 30 a head 37, one face of which is curved as shown at 38. A clevis 39 is swingingly carried, as shown at 40, on the part 29 and this clevis is provided with a transverse extension or cam 41 having a curved face 42. This 35 curved face is adapted for engagement with the curved face 38 of the head 37. One knuckle portion 43 of the clevis is provided with a segmental set of teeth, forming a ratchet 44 and adapted for engagement with 40 said teeth is a spring actuated pawl 45.

The operation, uses and advantages of the invention are as follows:

It is first necessary to fill the tubes 21 and 23 with some liquid and this may be conveniently done through the medium of a gun attached to a pressure fitting 46 in the line 28. While this is being done, the piston 32 will be in the position shown in Figure 4 and the pistons 11 will be in the position shown in 45 Figure 2. The springs 20 must exert enough pressure after the liquid has filled the tubes to maintain the jaws out of work engaging relation or the position shown in Figure 1. The jerk or brake line is connected to the 50 clevis as is usual practice. The gates 2 and 3 are opened to admit work, such as the tubing shown at 15, after which the gates may be latched together. When the jerk line is operated, the extension 41 will cam or move 55 the piston pin 34 inwardly which will push the piston 32 and force the liquid ahead of the same, causing the liquid to become compressed and in turn exert a force against the pistons 11. When this occurs, the jaws will 60 be moved into work engagement and the 65

harder the jerk line pulls upon the clevis, the greater the pressure exerted against the liquid, and as a consequence, the greater the pressure of the jaws against the work. When the jerk line or brake line is released, the jaws are urged into a neutral position or out of work engagement through the medium of springs 20 and the piston 32 will therefore move back to the position shown in Figure 4 because the liquid has been forced back through the pipes or tubing 21 and 23 by the pistons 11. However, it will be seen upon inspection of Figure 1 that when the jerk or brake line moves the clevis, the ratchet pawl 45 will engage the teeth 44 and will prevent the jaws from releasing the work. Thus, it will be necessary to release the pawl from the ratchet teeth before the jaws may be released from the work. The pawl may not be maintained in engagement with the ratchet unless desired but oftentimes after tubing has been screwed to a coupling, it is necessary to have a final cinch thereon and in which instance it is desired that the jaws be kept in work engagement.

The use of the cup rubbers prevents leakage of fluid in the sealing portions and, furthermore, it is evident that I have provided what may be termed an actuating piston, being the piston 32, and one or more actuated pistons 11 for operating the jaws.

It is obvious that various changes and modifications and variations may be made in practicing the invention in departure from the particular showing of the drawings without departing from the true spirit of the invention.

I claim:

1. The combination in a tongs provided with a head and a handle joined thereto, of a work engaging jaw carried by said head, fluid actuated means for moving said jaw relative to the head, a fluid actuating means carried by the handle, said handle being provided with a clevis, and means on said clevis adapted to move said fluid actuating means when the clevis is moved.

2. The combination in a tongs provided with a head and a handle joined thereto, of a work engaging jaw carried by said head, fluid actuated means for moving said jaw relative to the head, a fluid actuating means carried by the handle, said handle being provided with a clevis, means on said clevis adapted to move said fluid actuating means when the clevis is moved, and means for holding said clevis in a determined position.

3. A tool of the character described including, a handle, an object engaging head on the handle, a gripping member for engaging the object, and means for operating the gripping member including fluid pressure actuated means for moving the gripping member, a piston operable in an opening in the handle to supply fluid under pressure

to said fluid pressure actuated means, a clevis on the handle, and cam means operatively connecting the clevis and said piston.

4. A tool of the character described including, a handle, an object engaging head on the handle, a gripping member for engaging the object, and means for operating the gripping member including fluid pressure actuated means for moving the gripping member, a piston operable in an opening in the handle to supply fluid under pressure to said fluid pressure actuated means, a clevis on the handle, a stem on the piston, and a cam on the clevis for cooperating with the stem to actuate the piston.

5. A tool of the character described including, a handle, an object engaging head on the handle, a gripping member for engaging the object, means normally yieldingly holding the gripping member in an unactuated position, and means for actuating the gripping member including fluid pressure actuated means for moving the member, fluid pressure actuating means on the handle, a clevis on the handle, and means on the clevis for actuating the fluid pressure actuating means.

6. A tool of the character described including, a handle, an object engaging head on the handle, a plurality of gripping members carried by the head for engaging the object, and means for operating the gripping members including a fluid pressure actuated means for moving each gripping member, a single cylinder and piston fluid pressure actuating means carried by the handle, a clevis on the handle, and cam means operatively connecting the clevis and the said cylinder and piston means.

In testimony whereof, I have signed my name to this specification at Los Angeles, California, this 27th day of February, 1930.

FREDERICK IRA BARKIS.
